UNITED STATES PATENT OFFICE.

WILLIAM A. JAMESON, OF NIAGARA FALLS, NEW YORK.

DESIGN FOR A HANDLE FOR SPOONS, FORKS, OR SIMILAR ARTICLES.

SPECIFICATION forming part of Design No. 30,454, dated April 4, 1899.

Application filed February 21, 1899. Serial No. 706,300. Term of patent 7 years.

To all whom it may concern:

Be it known that I, WILLIAM A. JAMESON, a citizen of the United States, residing at Niagara Falls, in the county of Niagara and State of New York, have invented and produced a new and original Design for the Handles of Spoons, Forks, or Similar Articles, of which the following is a specification, reference being had to the accompanying drawings, forming part thereof.

The leading features of my design consist in the peculiar outline of the handle and the ornamentation of the obverse and reverse sides thereof, the obverse side, especially the upper portion of the handle, having oppositely-disposed marginal foliated scrolls, surmounted by radially-projecting scrolls separated by beaded strips and bearing a fleur-de-lis-like ornament.

Figure 1 is a view of the obverse side of a spoon, showing my handle attached to the bowl thereof; and Fig. 2, a reverse side of the same.

In the drawings, the letter *a* indicates the bowl of a spoon or the tines of a fork, the latter being shown by dotted lines, to which the handle is attached, and *b* the handle. A short distance from the junction of the handle with the bowl the marginal edges of the handle are approximately parallel to about midway of its length or to the point *c*, where they curve slightly outward and then abruptly inward at *d*. From this point the edges swell slightly outward, and then with an inward curve they again swell slightly outward to the point *e*. From the point *e* the edges take a gradual and graceful outward and inward curve to the point *f*, and from this point to the meeting point the edges are a series of scallops.

On the obverse side of the handle, at the junction of the handle with the bowl of the spoon, is a transverse scroll *g*, having a bead ornament beneath and surmounted by two oppositely-disposed cornucopia-like scrolls *h*

and a leaf *i*. Extending from the cornucopias *h* to the point *c* each edge is ornamented with a marginal bead or thread *j*, and between the marginal beads is a bead *k*, the latter being of much greater prominence than the beads *j*. The upper ends of the beads *j* terminate in inwardly-curved scrolls *l*, and continuing from these scrolls the marginal edges are ornamented with foliated scrolls *m*, extending up to the point *e*, from which point said marginal edges are ornamented with beads *n* and *o*, the latter being more prominent than the former. These beads are lost in the foliated scrolls *p*, which ornament the marginal edges to the point *f*, and interposed between the ends of the said foliated scrolls is a representation of a fleur-de-lis *r*, surmounted by radially-projecting scrolls *s*, having knob-like ends and separated by beaded strips *t*. The center panel *u* is convex in cross-section, and between it and the upper end of the central bead *k* is interposed fleur-de-lis ornament *v*. The central panel is partially inclosed by a scroll *w*, which extends from the fleur-de-lis *r* to the point *e*, where they terminate in outwardly-curved scrolls *y*. On the reverse side of the handle the marginal outline is very generally preserved, except that the extreme upper end of the handle terminates in a slightly-exaggerated fleur-de-lis ornament, and the lower end of the panel and upper end of the central bead are separated by an interposed round bead *z* instead of a fleur-de-lis, as on the obverse side.

Having thus fully described my invention, what I claim as new, and desire to secure by Letters Patent, is—

The design for the handle of a spoon, fork, or similar article, as shown and described.

In testimony whereof I affix my signature in the presence of two witnesses.

WILLIAM A. JAMESON.
